CLAIM

The ornamental design for a combined filter and double hinging bracket for attachment to a CRT monitor, as shown and described.

DESCRIPTION

FIG. 1 is a three-quarter left, top front perspective view of a combined filter and double hinging bracket for attachment to a CRT monitor, showing my new design; FIG. 2 is a vertical left side view of my new design, the right side view being a mirror image thereof; FIG. 3 is a top plan view thereof;

FIG. 4 is a left side elevational view thereof, the bracket shown separately from the filter sheet and the end plug for clarity of illustration, on an enlarged scale;

FIG. 5 is a rear elevation view of my new design; and, FIG. 6 is a bottom plan view of my new design.
